RADIO SWITCHING CONTROL

Application filed December 11, 1926. Serial No. 154,066.

The present invention relates to control means in electric circuits connected to sound amplification apparatus such as radio receiving circuits and the like. The invention relates more particularly to switching connections for cutting off and cutting in volume control apparatus in the sound amplification circuit before the sound amplification reaches a predetermined point, or immediately upon the beginning of tuning from a minimum volume position of the tuned part.

Various objects and advantages of the invention will be obvious from the following particular description of one form of apparatus embodying the invention or from an inspection of the accompanying drawing; and the invention also consists in certain new and novel features of construction and combinations of parts hereinafter set forth and claimed.

In the accompanying drawing there is shown for purposes of illustration one form of device embodying the invention and a circuit therefor, in which

Fig. 1 is a diagrammatic view in perspective showing somewhat diagrammatically an embodiment of the invention,

Fig. 2 is an end view of the apparatus of Fig. 1 in a different position of adjustment, and

Fig. 3 is a diagram of connections of apparatus including the embodiment of the invention.

In Fig. 1 the adjustable coil 1 which is loosely coupled with the coil 3 is mounted on the tuning shaft 5 which carries at one end the adjusting knob 7 and at the other end the mercury switch 10 for connection to a control part of a circuit in which it is used. The said coil 1 is at a position of minimum coupling with said coil 3 and the switch 10 is in the open circuit position. The inductance coil 1 which is coupled with coil 3, may be moved in a clockwise direction. It will be

seen as indicated in Fig. 2 that the switch 10 will be closed before any effective coupling will be made such as to produce any substantial volume from amplifying apparatus connected thereto or therethrough, it being understood of course that at a minimum cou-

pling no perceptible or at least small volume of sound will be produced. It will thus be seen that in a radio receiving set having a loud speaker which would be disagreeably loud if turned on suddenly at full volume, such a mode of operation will be prevented because the energizing switch will be closed at a point near the point of production of minimum volume and will then remain closed, so that the volume of sound must be increased from a minimum to the maximum without the possibility of the circuit suddenly being closed to produce the maximum volume of sound. In Fig. 3 of the drawing the switch 10 is connected in series with the filament 12, and the A battery 14. The switch 10 through the shaft 5 is mechanically connected to the movable coil 1 which is loosely coupled with the coil 3 which is connected in series between the audion plate 16 on one side and through the telephone or loud speaker 18 and B battery 20 to a point between said filament 12 and said switch 10. The grid 22 of the audion tube of which the filament 12 and plate 16 are other elements is connected through the grid leak and condenser unit 24 to said stationary coil 1 of the tuned couple, thence through the coupling coil 26 and from there to point between said filament 12 and said A battery 14. An antenna 30 connects through a coil 32 which is in tuned coupled relation to said coil 26 thence through the variable condenser 34 to a ground connection. This circuit has been used to illustrate the application of the present invention but it is to be understood that the invention can be applied with the switch 10 connected in any part of the circuit to provide that the circuit is not closed except when the variable elements are in such relation as to provide that sound production is brought from a minimum through gradations to any full or powerful value.

A mercury switch has been illustrated in the element embodying the invention and in the circuit in which the element is illustrated because a mercury switch is preferred for this purpose. It has certain advantages highly desirable in a radio receiving set for example

because it permits of smooth and gradual adjustment of a current control element without any restriction on a continued and gradual adjustment such as would be made by a switch having for example comparatively stiff spring connection members. In securing this effect, I am not limited either as to the type of volume control or the type of switch device used. The volume control may 10 for example be either a variable regeneration control, a variable filament control for the radio amplifier tubes, a potentiometer on the secondary of an audio-transformer, or any of the other methods of volume control known 15 to the art. As an alternative, there might be shown in place of a variable tickler coil, a variable condenser used as a regeneration control, a variable resistance used as a filament current control or even a variable antenna coupling device in the form of a movable 20 coil. The mercury switch also provides a simple means for keeping the circuit closed through the 90° of movement from minimum to maximum coupling and for breaking the 25 circuit when the element is returned to the uncoupled position.

While I have shown and described and have pointed out in the annexed claims certain novel features of the invention, it will be 30 understood that various omissions, substitutions and changes in the forms, parts and details of the devices illustrated and in their 35 operation and connection to and in electric circuits may be made by those skilled in the art without departing from the spirit of the 40 invention.

I claim:

1. In combination in a radio circuit, a 45 source of energy, a work circuit, a variable inductive coupler for energy transfer between 50 said source and said work circuit, and means including a mercury switch actuated simultaneously with said coupler to prevent the initiation of energy transmission from 55 said source to said work circuit except when said coupler is adjusted for minimum energy transfer.

2. In a radio circuit, a source of energy, a 60 work circuit, a variable inductive coupling between said source and said work circuit for the transfer of energy, means for starting and stopping said energy transfer, and means whereby said energy transfer can be initiated only when there is a minimum of coupling 65 between said source of energy and said work circuit.

3. In a radio circuit, a source of energy, a 70 work circuit, means for transferring energy from said source to said work circuit, comprising a thermionic tube and a variable coupler, means for closing the filament circuit of said tube to a suitable source of energy, and means whereby current flow through said 75 filament circuit can be initiated only when

said coupler is set for a minimum rate of energy transfer.

Signed at Hoboken in the county of Hudson and State of New Jersey this 8th day of December A. D. 1926.

LEROY J. BUTTOLPH.
